UNITED STATES PATENT OFFICE.

ERNEST B. COOKSEY, OF ST. LOUIS, MISSOURI, ASSIGNOR TO INTERNATIONAL SHOE COMPANY, OF ST. LOUIS, MISSOURI, A CORPORATION OF DELAWARE.

SHOE FORM.

Application filed February 25, 1927. Serial No. 170,791.

This invention relates to shoe forms.

An object of the invention is to provide an improved shoe form comprising a resilient element for exerting pressure outwardly 5 against the inner side of the shoe and for actuating a form for the inside of the toe portion of the shoe in close contact with the shoe to support the shoe upper and hold it in its intended shape.

10 Another object of the invention is to provide an improved shoe form comprising a form for the toe portion of a shoe and possessing the desired degree of resiliency, in combination with a resilient wire element 15 having its front ends connected to the toe form in a novel manner so as to utilize the resilient characteristics of the wire, which wire imparts outward pressure against the shoe upper.

20 Another object of the invention is to provide an improved shoe form designed and adapted specially for use by salesmen and others to permit handling and shipment of the shoes without danger of the shoe uppers 25 becoming pressed out of shape. In this connection, it will be noted that the device may also be used with advantage in stores and display rooms and elsewhere.

Other objects will appear from the following description, reference being made to the drawing, in which

Fig. 1, by dotted lines, indicates the outline of a shoe having my improved shoe form mounted therein.

35 Fig. 2 is a plan view of the device removed from the shoe.

Fig. 3 is a cross sectional view on the line 3—3 of Fig. 2.

In the specific embodiment of the invention shown, which may be varied within equivalent limits, as desired, I have provided a toe form 1 of a shape and configuration to fit closely within and support the toe portion of the shoe upper. This toe form may be 40 made from a sheet of celluloid or other material possessing the desired degree of resiliency. The sheet is folded and shaped substantially as shown so that the main portion of the sheet fits against the inside of the toe 45 upper, while an inturned flange 2 is obtained by bending inwardly the lower edge of the sheet of which the device is formed. The flange 2 is connected by a transverse strip 3 which as shown comprises two pieces of 50 celluloid or the like embracing the flange 2

at opposite sides of the device between them and secured to said flange by adhesion or otherwise. The strips 3 may be further united by a central eyelet 4 and a pair of laterally disposed eyelets 5.

60 The holder for this improved toe form comprises a loop of wire 6 curving upwardly and rearwardly from the toe form so that the main side and rear portions thereof will exert outward and rearward pressure against the inside of the shoe upper, as will be understood by reference to Fig. 1. The forward ends of this wire 6 have rearwardly rebent portions 7 which curve respectively toward the opposite side of the toe form 70 (Fig. 2) and have their extremities firmly engaged with the respective eyelets 5. Thus, a resilient wire holder for the toe form is provided, the resiliency of which is utilized to hold the sides of the upper properly 75 spread apart and to press the toe form into the toe of the shoe.

The device may be readily applied and removed from a shoe, may be manufactured at a comparatively low cost and possesses sufficient strength to be enduring. The specific form and relationship of the parts and the material thereof may be varied as desired within equivalent limits and I do not restrict myself unessentially in this or other particulars, but what I claim and desire to secure by Letters Patent is:—

1. A shoe form comprising a hollow resilient form arranged to fit within the toe of a shoe, and a connection uniting the lower edges of the opposite walls of the form, in combination with a wire loop arranged to fit within and press outwardly against the rear and sides of the shoe upper and having its ends within the form, a rearwardly extending rebent portion in connection with each forward end of said loop, and means securing the extremities of said rebent portions to said connection.

2. A shoe form comprising a hollow resilient form arranged to fit within the toe of a shoe, and a connection uniting the lower edges of the opposite walls of the form, in combination with a wire loop arranged to fit within and press outwardly against the rear and sides of the shoe upper and having its ends within the form, a rearwardly extending rebent portion in connection with each forward end of said loop, and means securing the extremities of said rebent portions

to said connection rearwardly from the bends of said rebent portions leaving said bends free and resilient within the form.

3. A shoe form comprising a resilient sheet shaped to fit within the toe of a shoe, and having its lower edges turned inwardly, and a connection uniting said edges between the ends of the form, in combination with a

wire loop arranged to press against the rear of the shoe upper and having its ends extending into said form above said connection, a rearwardly extending rebent portion in connection with each forward end of said loop, and means connecting the extremities of said rebent portions to said connection.

ERNEST B. COOKSEY.
